MULTIPLE UNIT FLOATING DRY DOCK

Frederic R. Harris, New York, N. Y.

Application April 9, 1943, Serial No. 482,376

28 Claims. (Cl. 114—46)

This invention relates to floating dry docks, and has for its principal object to provide an exceedingly mobile and highly serviceable dock made of separate parts which can be propelled or towed about expeditiously from place to place; and are capable of being assembled for use in one location and then readily divided and transferred to another as need may arise.

In its preferred form the invention embodies an improved floating dry dock comprising individual units, each of which has a pontoon hull and sections of side or wing walls, and which can be dispatched separately to the chosen site and there assembled with the other units; or detached for separate removal to a new location; where the units will be reassembled in the same manner as before.

In principle the invention relates to a dock comprising units, each of which has the side or wing wall sections on the pontoon hull not fixed but movable; so that they can be folded or laid down horizontally to diminish wind resistance when the hull moves about; and easily raised to upright position. Thus the hull is rendered more seaworthy and can be transferred from place to place at higher speed and with less expenditure of power.

The invention is well adapted to provide what is termed, in naval operations, an advance base dock; that is, a dock to be available in waters which are not very remote from the sphere of naval action; to enable quick repairs to be made to damaged or crippled warships; because the design of the dock enables the units to move at fairly good speed over considerable distances to the scene of use; be assembled there; and afterwards taken apart, sent somewhere else and reassembled as required.

It is a feature of the invention that each unit of the dry dock is constructed with a pontoon hull having ship characteristics. Each pontoon hull has a bow and stern of reduced width, and preferably pointed; and carries its own power generating apparatus and propulsion equipment for driving the unit through the water as a ship.

The units are placed side by side to make the complete dock; that is, the longitudinal axis of each separate pontoon hull extends transversely of the assembled dock. Means are provided on the sides of the several hulls for holding the units in alignment with one another before connecting them in final position. Fastening devices on the wall sections secure the sections rigidly together, end to end; in order to withstand more effectively the stresses imposed on the dry dock when loaded.

Another feature of the invention resides in the bow and stern construction of the individual hulls, which are made with bottoms that rise progressively higher toward the ends of the hull so that the free water surface area within the units decreases as the pontoon hull is pumped out. The bottoms are shaped so that the free water area in each unit begins to decrease before the loaded dry dock rises to a height that just lifts a ship 10 therein clear of the water. Each pontoon hull is preferably made with a central transverse buoyancy chamber which aligns with similar chambers in the other units; and in combination with the rising bottom for decreasing the free water area, materially reduces the stresses on a loaded pontoon hull.

Each of the wall sections of the respective units has a crane track extending along its top. When the units are assembled to make the dock, the 20 tracks on the walls of adjacent sections are joined together to provide a continuous track extending along the full length of the dry dock. Such a track is preferably provided on both of the complete wing walls of the assembled dock.

25 A further object of the invention is to provide novel means for transferring a crane from the pontoon deck of one unit to the top of a wall section of another unit. This is desirable in order that a crane may be loaded on the pontoon deck when an individual unit is equipped to go to sea; and moved later to the top of the wall section of another unit when the units are to be assembled to set up the dock.

An additional feature of the invention is the 30 method by which the wall sections are folded or raised by controlling the buoyancy of the sections and the pontoon hull to which they are connected. Yet another feature resides in the hinged connections between the wall sections and the pontoon hull, and the means for making changes in the 35 relative position of a wall section on its pontoon hull. Such changes are in the nature of adjustments of the hinged connections so as to effect accurate setting of the wall sections on one pontoon hull with respect to the corresponding wall sections on the adjacent pontoon hulls when connecting the individual units to one another.

40 Other objects, features and advantages of the invention will appear or be pointed out as the specification proceeds.

In the drawings forming a part hereof, in which the same reference characters denote the same parts in all the views,

45 Figure 1 is a side elevation, on a small scale,

showing one unit of a dry dock embodying this invention;

Figures 1a and 1b illustrate fastening means for the wall sections when vertical; and show how the sections are released for lowering;

Figure 2 is a view similar to Figure 1, but showing the dry dock unit with the side wall sections folded down on the pontoon deck in their sea-going position;

Figure 3 is a front view, partly broken away and on an enlarged scale, of the dry dock unit shown in Figure 2;

Figure 4 is a longitudinal sectional view, on the line 4—4 of Figure 3, showing the progressive rise in the pontoon bottom toward the end of the pontoon;

Figure 5 is a top plan view, on a reduced scale, showing the manner in which a number of individual units are brought together side by side to make the complete dock;

Figure 6 is an enlarged end view of one of the units shown in Figure 5 connected with adjacent units that are mostly broken away in the illustration;

Figure 7 is a side elevation of two units, one of which is submerged, in position for transferring a crane from the pontoon deck of one unit to the top of the wall section of the submerged unit;

Figure 8 is a top plan view of the dry dock units shown in Figure 7;

Figures 9 and 10 are enlarged sectional views through the one type of engaging means for securing the dry dock units together;

Figures 10a and 10b are respectively a plan and an end view of a different form of engaging means;

Figures 11 to 15 are diagrammatic side elevations illustrating a novel method by which the wing wall sections are raised and folded;

Figure 16 is an enlarged detail view of the hinged connection between a wing wall section and its associated pontoon;

Figure 17 is a sectional view on the line 17—17 of Figure 16; and

Figures 18 and 19 are respectively a side and a top view of means for admitting water to the wall sections when upright and draining it therefrom.

The dry dock unit shown in Figure 1 includes a pontoon hull 20 to which are connected hollow, side or wall sections 21 and 22. These wall sections are joined to the pontoon hull by hinges 23 along the lower inside edges of the wall sections. The upright position of the wall sections 21 and 22, shown in Figure 1, is the position that they occupy in the assembled dock. When standing thus, the wall sections are all firmly secured to the hulls outside of the hinges 23, to insure against accidental folding or dropping of the sections when the dry dock is in use. Hooks, fastening bolts, or any other suitable means are indicated in Figure 1a, consisting for example of bolts 18 in flanges 17 on the sections, to screw down into suitable holes in beams 19 on pontoon hulls 20, and held by nuts on their ends.

As illustrated in Figures 6 and 8, for example, both ends of each pontoon are vertical, and the outline of the vertical extremities is approximately Y-shaped. The exterior surface between the arms of the Y is plane or flat; outside of the Y it is curved, and in each vertical longitudinal plane from the center of the ends to the upper ends of the arms of the Y, the curve becomes longer and higher till it extends over the entire distance between bottom and deck. (See Figure 4). The shape of the hulls and the ends thereof

and the inside framework are not part of the invention of this case, but are fully set forth in my companion application, Serial No. 497,784, filed August 7, 1943, for Dry dock construction.

5 The hull 20 is made with a central buoyancy chamber 25 which is divided by a 'tween-deck into crew's quarters 26 and a machinery room 27. The floor 21' of the machinery room forms, in effect, a double or false bottom above the real bottom; and the intervening space between the bottoms can be divided into tanks or bunkers; or otherwise used.

10 Each wall section has an inside platform or deck 28, and on the top of the wall sections there are crane tracks 29. The decks 28 are air-tight and water-tight so that the pontoon hulls can never be sunk entirely.

15 Figure 2 shows the sections 21 and 22 folded down on the deck of the pontoon hull 20. This is their sea-going position. A pilot house 30 is located on the upper side of the wall section 21 when the dock unit is to be used as a ship. This pilot house is preferably removed before the sections are swung up into the operative position shown in Figure 1. Provision may be made for locating the pilot house on a support outside of the wall section 21, when the latter is in upright position.

20 Each hull 20 has anchors 31 supported by anchor chains that extend through hawser holes in the bow and stern of the hull!

The shape of the pontoon hulls is the same at both ends, and the units are provided with twin screws 32 and twin rudders 33. The screws 32 are supplied with power from machinery in the room 27 of the chamber through a Diesel-engine electric drive. The rudders 33 are controlled from the pilot house 30. The engines, the transmission devices between them and the propellers, and the connections from the pilot house 30 to the rudders are not shown herein, as they are not a part of this invention.

25 When the forward wall section 21 is down in folded position, it overlaps the crew's quarters 26 and the portion of the wall section beyond the deck 28 at what is the upper end when the section is raised, forms a compartment 34 that is used as a captain's cabin and radio room. Access between the radio room and crew's quarters can be had through an enclosed passage or hatchway 35 that opens through the pontoon deck. The entrance to both hull and wall section can of course be closed when the latter is lifted, and the passageway itself removed or withdrawn inside the wall or hull. This feature is not a part of the invention of this case, but is fully described in my application Serial No. 482,375 for patent on a Pontoon unit for floating dock filed of even date herewith.

30 When the wall sections are folded or lowered, and the dry dock unit is in use as a ship, for transfer to another place, the upper sides of the two sections may be connected by a bridge or walk 36, and railings 37. This walk is removed when the sections are to be raised.

35 The wall sections 21 and 22 extend across the full width of each hull 20 as indicated in Figure 3. Each hull 20 is pointed near the bottom and for a distance equal to about one-half the height of the hull, the upper part of the bow and stern are made with a generally triangular flat, end surface 39. This construction does not materially affect the sea-worthiness of the units in towing or self-propulsion.

40 Although each pontoon bottom is level along

substantially the entire length of the keel, as shown in Figures 1 and 2, the bottom rises at the bow and stern, on either side of the longitudinal center plane of the hull, as is best illustrated in Figure 4. This figure shows an outside water line 40 and a free water surface 41 within the hull. As the pontoon hull is pumped out, and the dock rises higher in the water, the free water area 41 contracts in such a way that progressive pumping adds no further buoyancy to the ends of the hull, but concentrates the additional buoyancy effect nearer to the center, where the ship load is concentrated.

This feature of reducing the free water surface area within each pontoon hull in such a way that buoyancy is added toward the center of the hull as the dock rises to its position of maximum load, is described in my patents, Nos. 2,291,076 and 2,291,077, issued July 28, 1942. By increasing the buoyancy nearer the center as the dock rises to its position of maximum load, the stresses on the dock are reduced and the dock may be of lighter construction.

With the present invention the reduction of the free water surface area is of particular importance in practice, because of the extent of the pontoon hulls beyond the wing wall sections. This construction increases the span of the pontoon hull beyond that of a conventional dock of equal capacity in which the hull of the pontoon does not extend beyond the outer faces of the side walls.

Figure 5 shows a number of identical dock units 20 positioned side by side and connected together to form a complete dry dock. A dock of any desired length can be made by increasing the number of separate units.

The manner in which the units are connected together is shown in Figures 6 and 10. There are tapered socket members 44 on the side of each hull 20, and a similar socket member on the side of each wall section. Tapered heads 45 on the near side of the next adjacent dock unit, hull and wall section, fit into the socket members 44 and align the individual units with one another. The same devices unite the other sides of these units to the next unit. Connector plates 46 on the outer faces of the respective wall sections are joined together by tie plates 47, which may be detachably fastened to the connector plates, but are preferably secured by welding. When the dry dock units are connected together by welding and it becomes necessary to separate them, the tie plates 47 are cut apart with a torch. It will be observed that these engaging devices between the adjacent units, as well as the fastening provided by the connector plates, are widely spaced in a vertical direction to provide the dock with maximum strength against sagging or hogging stresses.

Figures 10a and 10b show a different type of fastening or engaging devices, consisting of retaining members fixed at the sides of the hull and wall sections of the units. When these members engage, a member 44a receives a head 45a, the former having a horizontal slot 44b with undercut edges 44c. The member 45a has a shape like a short length of steel rail, with base, web and head; the heads may be tapered at the ends; and the slots 44b may have expanded or flaring ends to facilitate the entrance of the heads of the members 45a. Engagement is accomplished by movement of any hull lengthwise when these engaging devices are aligned. The members of each pair of devices are locked together by plates

or retaining elements 44d held on the ends of the members 44a by suitable bolts. Thus it is easy to effect the removal of any of the units 20 out of the line as illustrated in Figure 5 for self-docking on the other units and repair or cleaning. The hinges 23 of the wall sections on the unit are simply dismantled and all other connections removed between the pontoon hull of a unit and its wall sections 21 and 22, which are now secured to the wall sections of the units at each side. The plates 44d are taken off, the hull shifted to pull the members 44a and heads 45a free; and the hull without its wall sections can then be fully withdrawn by pulling it from under the side walls. Later it can be reinstalled or even wholly replaced. For the same purpose the devices 44 and 45 may be removable, if desired.

Although the wall sections on adjacent units do not have their sides in contact with one another, 20 the crane tracks 29 along the tops of the walls are fastened together by connecting members to form a continuous track for a crane. Figure 5 shows crane tracks 29 along the tops of both of 25 the wing walls of the assembled dry dock. A crane 48 on each of the dry dock wings is capable of reaching at least one-half way across the dry dock.

When the wall sections 21 and 22 are folded down into sea-going position, each of the cranes 30 48 is carried on the deck of one of the pontoon hulls 20 on tracks 49 extending across the pontoon deck between the folded wall sections, as shown in Figure 2. The crane 48 is indicated in broken lines.

35 When the dry dock is being assembled, and it is necessary to transfer the crane 48 to the top of a wall section, the transfer is done as illustrated in Figure 7. One of the pontoon hulls is submerged until the crane tracks on the top of 40 its wall section 21 come into alignment with the crane tracks on the deck of a floating pontoon hull bearing the crane, designated in Figure 7 by the reference character 20'.

To facilitate exact positioning of said wall section with respect to the pontoon 20' for this purpose, tapered heads 45 are provided on the side of the pontoon hull 20' and the upper portion of the wing section receiving said crane. When the tapered heads 45 are engaged in the socket 50 members 44, the wall section and unit can be held together by a swivel bolt 53 on the wall section, for example, that swings into a slot 54 in a hook 55 extending from the hull 20'. A nut 56 threaded on the free end of the swivel bolt 53 can be screwed further up on the bolt to secure the wall section to the pontoon hull 20' while the crane is being transferred from the pontoon deck to the top of the said wall section.

Figure 8 shows the relative positions of the 55 floating pontoon hull and the submerged pontoon hull when in position for transferring the crane as shown in Figure 7. It will be evident that if the crane 48 were to be transferred from the deck of the pontoon hull 20' to the top of the other wall section on the submerged pontoon hull 20, the latter would be merely shifted lengthwise of itself until the other wall section occupied the right position. In this way cranes can be mounted on both tracks 29, as indicated 60 in Figure 5.

Each wall section will have flues 57 opening through the deck 28 and the top for escape and entrance of air from the water space in the wall sections below the decks 28; and necks or 65 conduits 58 on the inner face near the bottom for

the admission and escape of water; as shown for one hull only in Figure 8; being omitted elsewhere for the sake of clearness; but it will be understood that they are provided in all the wall sections. Flues 57 do not communicate with the spaces above decks 28.

Figures 11 to 15 illustrate the method by which the wall sections are raised. In Figure 11 the pontoon 20 is shown with the sections 21 and 22 in their lowered or folded, sea-going position. When it is desired to raise the bow section 21, for instance, into an upright position, it is first released from any connections with the pontoon deck that would prevent turning at the hinges 23, and all openings that would admit water to any space in the pontoon or the wall section used by the crew are closed. Necks 58 of course are open. The pontoon hull 20 is then flooded until both ends are below the water level 40, as shown in Figure 12. Water is allowed to run into the hull in such wise that the bow of the pontoon hull 20 is submerged for a considerably greater depth than the stern. The water also enters the section freely through the necks 58. As soon as the pontoon hull begins to sink the section 21 begins to swing up, because of its buoyancy, to the position shown in Figure 12. As the bow sinks deeper, the water rises in the section 21, and the center of gravity of this section and the water therein shifts forward. As soon as the center of gravity reaches an "off-center" position; that is, moves into a vertical plane between the hinge and the bow, the section 21 will be over-weighted forward of the hinge and settle into upright position as in Figure 13. No forces other than gravity and buoyancy are needed. But if desired the operation may be assisted by a pull on a cable 58' attached to a capstan (not shown) on the pontoon hull and to the top of the section 21.

The water in the hull 20 is now pumped out until the pontoon hull rises to the position shown in Figure 13. The section 21 is then fastened to the pontoon deck to prevent accidental folding, and the water in it flows out through the necks 58. Next the section 22 is released from the pontoon hull so that it is free to swing on its hinges 23. Pontoon hull 20 is again submerged, the flooding of the pontoon compartments being controlled so as to sink the stern to a greater depth than the bow, and the section 22 is lifted, the proceeding being the same as with section 21.

All the other sections are raised to stand on the pontoon decks in the same manner.

The sections are also folded by flooding the pontoon units. For example, if the section 22 is to be lowered, all fastening means preventing movement about the hinges 23 are disconnected and the pontoon hull 20 is submerged into substantially the position shown in Figure 14, with both ends under water and the stern lower than the bow. This at once causes the section 22 to tilt forward or inward. To control the section, valves in the necks 58 are opened, but not so much as when the section was lifted; and its fall is checked. It then comes down slowly to the deck, being cushioned by the water forward of its hinges. Otherwise its drop would be too rapid. By means of the valves in the necks 58, the shift of the center of gravity of the section 22 toward the bow till it crosses a vertical line through the hinge 23, is nicely regulated. Also, a cable 82 and a capstan to pull the section 22 to the right may be employed, but is really not needed. At the start all openings that might admit water, except as required, are closed as before.

The ports or ducts 57 in the tops of the sections may be left open or provided with closures of any suitable kind. The necks 58 are more fully shown in Figures 18 and 19. A pipe length 59 in the form of a horizontal elbow is fixed to the section and united at its outer end by a ball-joint 59' to another elbow pipe 60, having one end formed to constitute part of the ball-joint 59'. The axis of this joint should preferably be in line with the axis of the hinges, the pins for which are engaged by bearing plates or lugs 61. The pipe length 60 is united by a ball joint 60a to a pipe length 60a, which may be secured to the pontoon deck and contain a valve 60b. These valves may be of any proper design and arranged to be controlled by connections indicated in outline only at 60c, inside the hull and leading, for instance, to points in the compartment or quarters 26. Such connections may be mechanical or electrical or may include an airline, and can be made by any one of ordinary technical skill. Swivel-joint conduits or piping of this general design are well known.

The connections for flooding and pumping out are not shown herein, but are fully disclosed and defined in the claims of my application Serial No. 482,374 for patent on Floating dry dock and pumping apparatus, filed of even date herewith. But each pontoon unit has inlet and discharge ports in the lower part of its hull connected by conduits with valves to the various compartments of the hull outside of the chamber 25, and pumps and engines to operate the system.

The method of raising and folding the sections 21 and 22 makes it possible to shift these heavy parts of the dry dock between raised and lowered positions, and vice versa, without the use of any special machinery for the purpose.

Figures 16 and 17 show one of the hinges 23 by which each wall section is connected with the deck of the pontoon hull 20, section 22 being shown as an example. This hinge is so constructed that it permits minor adjustment of the position of the section with respect to the pontoon deck. The hinge is made up of plates or bearing lugs 61 that are connected to and extend from the inner face of the section at the bottom, and other plates or bearing lugs 62 connected with the deck of the pontoon hull 20. A link 63 extends between the plates 61 and 62 and is connected with these plates by pins 64 and 65.

The link 63 has a recessed keyway 66 in which fits a key 67. The key 67 has upper flanges 68 that fit into side recesses of the keyway 66 and lower flanges 69 that engage undercut guides 70 secured to the pontoon deck. The flanges 68 and 69 of key 67 are convergent, making the key tapered, as shown in Figure 17; and the link 63 of hinge 23 can be raised or lowered by driving the key 67 to the right or left respectively, in Figure 17. By thus moving the key 67, each section may be raised or lowered along its hinged side to adjust the alignment of any section with other wall sections.

Opening through the pontoon deck is a port 71 (Figures 1a and 1b), in line with a port 72 in the bottom of each wall section when the latter is vertical. Thus the inside of the wall sections are put into communication with the pontoon hull and can be flooded and pumped out through the hull. As many of these ports are used as needed to connect the wall sections with the pontoon compartments beneath it. When the wall sections are down as in Figure 2, these ports 71 and 72 are closed, as by plates bolted or otherwise

secured over the ports. They are opened when the wall sections are raised, so that the sections and pontoon can be flooded and pumped out together. The crew's quarters in the pontoon are then connected through passageways to the spaces in the wall sections above the decks 28, as fully disclosed and in my application for patent on a Pontoon unit for a floating dry dock, aforesaid.

On the deck of each pontoon hull (Figures 1a and 1b) at bow and stern are fixed beams 19, to support the wall sections along the four edges of the bottom thereof. These beams have flanges at the top to be engaged by the bolts 18 which secure the wall sections in upright position. When the sections are to be raised, packing or gasket material 19' (Figure 16) may be laid on the tops of the beams to make a leakproof joint between them and the wall sections; and at one point or more under each section the beams may have an opening 13, with a screw plug 14, to admit air under the wall sections when they are to be lowered. The plugs 14 are then screwed out.

If desired one or more pipe necks 15 (Figure 1a) can be added to connect each wall section with the inside of the pontoon hull; particularly compartments between those directly below the wall sections and the chamber 25. These necks allow air and water to circulate when the hulls and wall sections are flooded or emptied. They can easily be removed. Necks 15 are only used when the wall sections are up, and removed when they are to be lowered.

To keep the air at the same pressure in all parts of the hull, the various compartments are in communication. For this purpose, openings 16 are made in the deck and connected by pipes 17. Each compartment is thus connected to every adjacent compartment, except when the wall sections are down. Then the pipes 17 are not in place and the openings 16 are closed.

The deck is also provided with air vent valves 18, beneath yokes 19, having bearing openings 20. Springs 21 hold these valves closed. Air can thus escape when water is admitted to flood the pontoon hulls. For sea-going positions of the wall sections, the valves are not in place and the openings 17 and vent valves are more fully described in my application covering the Floating dry dock and pumping apparatus aforesaid.

A dry dock of this design can be set up for use at one place and then taken apart and removed to another location and set up again. The units can either propel themselves by connection of the pumping engines, not shown, with the propellers 32, or be towed.

The invention has been described in its preferred embodiment, but changes and modifications can be made, and some features of the invention can be used without others.

Having described my invention, what I believe to be new and desire to secure and protect by Letters Patent of the United States is:

1. A floating dry dock made up of separate units, each of which has a ship form at its ends and bears transverse wall sections on its deck near bow and stern, means for pivotally connecting said sections to the deck, so that they can be laid down or stood upright thereon, and means for connecting the units together side by side to form the complete dry dock with said sections in alignment.

2. A unit for a dry dock including a hull of ship form at its ends, having wall sections on the

deck thereof, means for pivotally connecting said sections to the deck, so that they can be laid down or stood upright thereon, said deck extending at bow and stern beyond said sections.

5 3. A dry dock comprising units, each of which has a single pontoon hull, movable wall sections attached to each hull, each section being substantially as long as the width of the hull and having its ends flush with the sides thereof, and arranged to be laid down on the hull or stood upright to provide wall sections adjacent opposite ends of the hull, said ends being of ship form and extending beyond the wall sections.

10 4. The dry dock, according to claim 3, in which the units have engaging devices to fasten the units side by side, with said sections upright and in alignment across the bows and sterns of the units.

15 5. A dry dock unit with a hull, with a substantially flat keel and bottom of virtually uniform depth along the longitudinal center line of the hull, and rising laterally from the keel progressively higher adjacent both ends of the unit, to such a level that the free water surface within the hull decreases in area as the water is pumped out.

20 6. A dry dock unit with a hull having a bottom which is of virtually uniform depth along its longitudinal center line but rises progressively higher laterally from said center line adjacent both ends of the unit and to such a level that the water surface within the hull decreases in area as the unit is pumped free of water, the hull also having a centrally located buoyancy chamber 30 therein.

35 7. A dry dock unit including a pontoon hull having a deck, a wall section thereon, and hinge means having an axis extending transversely of the hull connecting the section to the pontoon hull so that the section may be raised to stand on said deck or lowered to lie thereon.

40 8. A dry dock unit including a pontoon hull, a wall section thereon, hinge means connecting the section to the hull, and means for adjusting the hinge means to effect minor changes in the position of the section with respect to the hull.

45 9. The method of folding a wall section upon a dry dock unit that has a pontoon hull and a hollow wall section movably connected thereto, said method comprising the sinking of the pontoon hull until a substantial part of the section to be folded is under water, flooding the section in the course of sinking as it changes position by buoyancy, unbalancing the section, and 50 lowering it on the deck of the hull.

10. The method of rearing the wall section of a dry dock that has a pontoon hull and a hollow wall section movably mounted thereon and resting on its deck, said method comprising the sinking 55 of the hull with the wall section free to swing upward, flooding the section, and raising the hull and allowing the wall section to settle down on the pontoon in upright position.

11. The method of getting the movable wall section of a dry dock unit into position on the deck of the unit, which comprises sinking the unit and pulling the section partly under water, allowing the section to move by its own buoyancy, weighting the lower portion of the section, and settling the section into stable position by forces including the action of gravity.

12. A dry dock comprising units, each of which has a pontoon hull with a deck and wall sections adjacent the opposite ends of the deck, said sections having their ends flush with the sides of

the hull, crane-supporting tracks on the deck of one unit and extending entirely across same, similar tracks on top of the wall section of another unit, and engaging means for holding the one unit with its deck in such relation to a wall section of the other that the crane-supporting tracks of said units are in alignment for transferring a crane between said units.

13. A dry dock pontoon hull with a wall section thereon, said section having hinged means connecting it to the hull, said means including a link pinned to the hull at one end and the section at the other and means for adjusting the position of said link.

14. A dry dock pontoon hull with wall sections thereon, said sections having hinged means connecting them to the hull, said means comprising a link, bearing lugs on the section and the hull to which the link is pinned at its ends, the link having a recess in one edge, a tongue engaging the recess, and guide members for movably securing the tongue to the hull, the tongue being tapered for adjustment of said means.

15. The method of lowering a hollow wall section reared upon a dry dock unit that has a pontoon hull and the hollow wall section pivotally connected thereto, said method consisting in sinking the hull until a substantial part of the section to be folded is under water, and tilting the section over by the action of its own buoyancy, flooding the section during sinking and then raising the pontoon hull to unbalance the section and lower it by gravity on the deck thereof.

16. The method of rearing the hollow wall section of a dry dock that has a pontoon hull and the hollow wall section pivotally connected thereto and resting on its deck, said method comprising the sinking of the hull with the wall section free to swing upward, thus tilting the section as said hull sinks, and then raising the hull and allowing the wall section to settle down on the pontoon by its own weight in upright position.

17. The method of getting the two wall sections of a dry dock unit into position on the deck of the unit, to which they have pivotal connection, which comprises sinking the unit till one section is partly under water, allowing it to move by its own buoyancy and weighting the lower portion of said section, then raising the unit and settling the section into stable position by forces including the action of gravity; and repeating said steps to set the other section.

18. A dry dock unit comprising a single pontoon hull, with a wall section substantially as long as the beam of the hull and having its ends flush with the sides thereof movably connected to the deck thereof adjacent the lower end to be laid down on the deck or placed upright thereon, the said hull being of ship form and extending beyond said wall section.

19. The dry dock unit according to claim 18, in which the section and the deck have openings which register when the section is upright, putting the inside of the pontoon hull into com-

munication with the inside of the wall section.

20. A dry dock unit comprising a pontoon hull with a deck, a wall section movably mounted on the hull, a conduit attached to the lower part of the section, said conduit having jointed parts one of which is affixed to the deck, and a controlling valve in said fixed part.

21. A dry dock comprising pontoon units to be aligned to form the dock, said units having means for securing them together comprising a retaining member with a head thereon, a receiving retaining member having undercut slots for said head, and plates for closing the ends of said slot when the head is engaged within 10 15 the slot.

22. A dry dock comprising pontoon units to be joined to form the dock, said units having engaging means to hold them in alignment, said means comprising a socket member and a head 20 to enter same, and a swivelled bolt to prevent separation of said units.

23. A single dry dock pontoon unit having a deck, a wall section substantially as long as the beam of the hull and having its ends flush with 25 the sides thereof movably mounted on the deck, beams having flanges to support the section and means for engaging the section and said flanges to hold the section in position, said unit being of ship form and extending beyond said wall 30 section.

24. A dry dock pontoon unit having a hull and a wall section thereon, beams on the deck for supporting the section, said beams having openings and removable closures for said openings, 35 the beams encompassing a closed space through which the interior of the wall section may be connected to the inside of said hull.

25. A dry dock unit comprising a pontoon hull with a deck, a wall section with hinged connection thereto, a conduit attached to the lower part of the section and comprising a joint in line with the pivot of said hinged connection, said conduit being secured to the deck and a controlling valve in the conduit.

26. A dry dock unit including a pontoon having a deck, a wall section thereon, and hinge means the axis of which extends transversely of the pontoon, for movably mounting the section on the deck so that the section can be lowered 50 to rest on the deck, or raised to stand upright thereon across said pontoon.

27. A dry dock unit including a pontoon hull, a wall section thereon, hinge means connecting the section to the hull so that the section can 65 be raised to stand upright or lowered to lie on the deck, and mechanical connections between the hull and section remote from hinge means for controlling the movement of the section.

28. A dry dock unit comprising a hull, a wall section, hinged means for connecting the wall section to the hull to be laid down or stood upright thereon, and connections between the hull and said section remote from said hinge means to control the movement of the section.

FREDERIC R. HARRIS.
